UNITED STATES PATENT OFFICE.

JENNIE L. NISBET, OF SYRACUSE, NEW YORK, ASSIGNOR OF ONE-HALF TO
ELLA M. KINNE AND HERBERT E. WRIGHT, OF SAME PLACE.

DESIGN FOR A GUIDE-PLATE FOR ACCOUNT-BOOKS.

SPECIFICATION forming part of Design No. 32,159, dated January 30, 1900.

Application filed January 2, 1900. Serial No. 179. Term of patent 7 years.

To all whom it may concern:

Be it known that I, JENNIE L. NISBET, a citizen of the United States, residing at Syracuse, in the county of Onondaga and State of New York, have invented and produced a new and original Design for a Guide-Plate for an Account-Sheet, of which the following is a specification, reference being had to the accompanying drawings, forming part thereof.

10 This plate is intended to be used in connection with a certain specially-printed account-sheet for the purpose of accurately guiding a person in making various entries upon said sheet.

15 In the accompanying drawings, Figure 1 is a perspective view of the guide-plate embodying my design, and Fig. 2 is a sectional view on line X X in Fig. 1.

20 As shown in the drawings, the leading or material features of my design are as follows, to wit: a plurality of ports *a a*, arranged in series of equal numbers and of equal dimensions and each series extending in a row horizontally part way across the sheet A and 25 disposed with its ports coinciding with those

of the adjacent rows; separate horizontally-elongated openings *b b* at corresponding ends of all of said rows of ports, with exception of the uppermost row in range therewith, at the corresponding end of which latter row is an 30 enlarged elongated opening *c* equal in length to the two subjacent openings *b b*; farther, enlarged horizontally-elongated openings *d d* at the opposite corresponding ends of the rows of ports *a a* and in line therewith and 35 the supplemental ports *e e* beyond the openings *b b* and adjacent thereto and respectively in line with the rows of ports *a a*.

Having described my invention, what I claim as new, and desire to secure by Letters 40 Patent, is—

The design for a guide-plate for an account-sheet, as herein shown and described.

In testimony whereof I have signed my name to this specification in the presence of 45 two subscribing witnesses.

JENNIE L. NISBET.
